UNITED STATES PATENT OFFICE.

CHARLES E. REDDIG, OF KEW GARDEN, NEW YORK, ASSIGNOR TO WESTERN ELECTRIC COMPANY, INCORPORATED, OF NEW YORK, N. Y., A CORPORATION OF NEW YORK.

IRONING MACHINE.

Application filed August 11, 1920. Serial No. 402,848.

To all whom it may concern:

Be it known that I, CHARLES E. REDDIG, a citizen of the United States, residing at Kew Garden, Richmond Hill, in the county of Queens, State of New York, have invented certain new and useful Improvements in Ironing Machines, of which the following is a full, clear, concise, and exact description.

10 This invention relates to ironing machines or mangles.

The general object of the invention is to provide a new and improved ironing machine which will be simple in construction and efficient and safe in operation. Among the characteristic features of the invention are an auxiliary ironing roll and shoe which permit the ironing of articles such as collars and cuffs which are not readily ironed by 20 the main ironing roll and shoe; an improved arrangement whereby the ironing shoe is yieldingly and removably held in co-operative engagement with the ironing roll; a feed table which also serves as a covering to 25 protect the ironing roll and shoe from dust; and a new and improved construction whereby the roll is disconnected from the driving mechanism when the shoe is moved out of engagement with the ironing roll.

30 Referring to the drawings, in which an ironing machine embodying the invention is illustrated, Fig. 1 is a front elevation, certain parts being broken away to permit illustration on a large scale; Fig. 2 is an elevation 35 of the right end of the machine as viewed in Fig. 1; Fig. 3 is a sectional end elevation on the line 3—3 of Fig. 1; Fig. 4 is an end elevation partly in section of the left end of the machine as viewed in Fig. 1;

40 Fig. 5 is a sectional front elevation of the gearing and clutch mechanism through which the ironing roll is driven; Fig. 6 is a sectional end elevation of the mechanism shown in Fig. 5; Fig. 7 is a plan view 45 partly in section of the mechanism by which the movement of the shoe and its pressure upon the ironing roll are controlled; Figs. 8, 9 and 10 are fragmentary end elevations illustrating the mechanism shown in Fig. 7 and the manner in which it operates; and Fig. 11 is a front elevation partly in section of the foot pedal for moving the auxiliary shoe.

Referring to the drawings, the various parts of the ironing machine are supported by frames 15 and 16 which are rigidly connected together by pipes which are threaded near their ends and carry nuts 17 which co-operate with the outsides and insides of the frames 15 and 16. One of these pipes serves 55 also as a conduit for gas, as will be herein-after explained. A main ironing roll 18, which may be covered with layers of fabric or felt in the usual manner, is rigidly secured to a shaft 19 which is mounted in 60 fixed bearings 20 and 21 in the frames 15 and 16. Cooperating with the main ironing roll 18 is a main ironing shoe 23 of any suitable and well known kind. The form of 65 this shoe is best shown in Fig. 3. Projecting from the bottom of the shoe 23 at each end thereof are brackets 24 at the end of which are elliptical holes into which project pins 25 mounted in the frames 15 and 16. By 70 thus making the pivotal mounting of the shoe 23 loose, the surface of the shoe is permitted to adapt itself to the contour of the ironing roll 18. The shoe 23 is yieldingly and removably held in engagement with the ironing roll 18, by means hereinafter 75 described in detail.

Mounted on the shaft 19 which projects beyond the outside of the frame 15, is an auxiliary ironing roll 28 which may be covered with fabric or felt in the same manner 80 as the main ironing roll 18. Co-operating with said roll 28 is an auxiliary ironing shoe 29 which is hollow and adapted to be used as hereinafter described. Said shoe 29 is pivotally supported in a yoke 30 which is 85 an integral part of a lever 31 pivoted on a screw 32 attached to the frame 15. The other end 33 of said lever is secured to a rod 34 which extends downwardly through a boss 35 projecting from the outer face of 90 the frame 15; and a spring 37, interposed between the boss 35 and the end 33 of the lever 31, yieldingly holds the auxiliary shoe 29 in engagement with the auxiliary ironing roll 28. The lower end of the rod 34 95 is secured to a treadle 38 of the form shown in Figs. 4 and 11, which is pivotally secured to the bottom of the frame 15. The movement of the treadle 38 in the direction of the arrow in Fig. 11 moves the rod 34 100 downwardly, thereby rotating the lever 31 105

against the tension of the spring 37 and moving the auxiliary shoe 29 out of engagement with the auxiliary roll 28. In order to provide for maintaining the shoe 29 out of engagement with the ironing roll 28, a latch 40, pivotally mounted in the treadle 38, is provided. This latch 40 has a shouldered end 41 which moves into engagement with a shoulder or notch in the bottom of the frame 15 under the influence of a spring 42, when the treadle is depressed, as will be apparent from Fig. 11. In order to release the latch 40 and allow the treadle 38 to rise, it is merely necessary for the operator to depress slightly the latch 40, thereby releasing the shouldered ends 41 from engagement with the frame 15 and permitting the treadle 38 to rise.

The power for driving the main and auxiliary ironing rolls 18 and 28 may be provided in any suitable manner as, for example, by an electric motor 45, bolted to the bottom of the table 46 which is supported by and mounted between the frames 15 and 16. The driving power of the motor is transmitted through a belt 48, to a pulley 49 secured to a shaft 50 mounted on bearings supported by the frame 16. Referring particularly to Figs. 5 and 6, it will be seen that the shaft 50 has rigidly secured thereto a worm pinion 52 which meshes with a worm gear 53 rotatably mounted on a shaft 54 extending vertically and journaled in bearings formed in a frame 55 bolted to the frame 16. Secured to the upper face of the worm gear 53 is a clutch member 56 adapted to cooperate with a complementary clutch member 57 which is rotatable with but slideable on the shaft 54. When the clutch members 56 and 57 are in mesh, the worm gear 53 drives the shaft 54 which at its top carries a beveled pinion 59 which meshes with a beveled gear 60 secured to the shaft 19 of the ironing rolls 18 and 28. The clutch member 57 at its upper end has a groove adapted to receive the ends 63 of a yoke which is rigidly secured to a shaft 64 mounted for rotary movement in the frame 16. Rigidly secured to the end of the shaft 64 within the frame 16, is a lever 66 carrying at its end a cam 67 adapted to cooperate with a pin 68 projecting from the end of the shoe 23, as best shown in Figs. 8, 9 and 10. The cam 67 is at all times held in engagement with the pin 68 by a spring 70 secured at one end to the cam 67 and at the other end to the frame 16. As will be apparent from Figs. 8, 9 and 10, movement of the shoe 23 from the position shown in Fig. 8 to the position shown in Fig. 10, causes rocking of the lever 66, rotation of the shaft 64 and rocking of the yoke 63 with consequent movement of the clutch member 57 out of engagement with the clutch member 56. The shaft 19 is thus connected with the driving mecha-

nism when the shoe 23 is cooperating with the ironing roll; and is disconnected from the driving mechanism when the shoe 23 is moved to its farthest position away from said roll.

Figs. 7, 8, 9 and 10 best show the means for yieldingly and removably holding the shoe 23 in cooperative engagement with the ironing roll 18. Pivotally mounted on bolts 75 extending from the inside of the frames 15 and 16, are cams 76 of the form best shown in Figs. 8, 9 and 10. Extending from these cams are arms 77 connected by a bar 78 which may be grasped by the operator and by which the cams 76 may be moved in unison. At each side of the machine is a spring 79 through which extends a rod 80 connected at one end to one end of said spring by the head 81 secured to said rod 80. The other end of said rod 80 is bent as shown in Fig. 7, and by a cotter pin 82 is secured in a hole in a lug 83 projecting from one edge of the cam 76. Near its middle portion, the rod 80 carries a loose collar 85 which is engaged by the spring 79; and said rod 80 also carries a collar 86 rigidly secured to said rod. The rod 80, at the portion between the collars 85 and 86 passes freely through a lug 88 bolted at one end to a boss 89 extending from the shoe 23. The hole through the boss 88 is made divergent, as shown in Fig. 7 in order to permit angular movement of the rod 80 in said hole during operation of the device. Rotatably mounted on the outer end of the lug 88 is a roller 91 adapted to cooperate with the edge of the cam 76. It will be obvious from Figs. 8, 9 and 10, that the cams 76 are so formed and the rods 80 are so connected thereto that, when in the position shown in Fig. 8, said cams allow the springs 79 to hold the shoe 23 in yielding contact with the ironing roll 18; and that, in the positions shown in Figs. 9 and 10, the shoe 23 is moved and held away from the ironing roll 18 at different distances. Moreover, the form of the cams 76 and the relations between them and the cooperating parts are such, that the cams 76 will stop and stay in any one of the three positions shown in Figs. 8, 9 and 10; and may readily be moved from one position to the next.

The main and auxiliary shoes 23 and 29 may be heated in any suitable manner. As shown, they are heated by gas flames furnished by burners 93 and 94 mounted inside of the shoes. Gas for the burners is supplied through a feed pipe 95 extending through the frames 15 and 16. Coupled to this pipe 95 is a jointed branch pipe composed of sections 96 and 97, the latter being pivotally connected to the burner pipe 98 extending to the shoe 23. Extending from the other end of the feed pipe 95 is another branch pipe 99 which is pivotally connected

to the pipe 95 at one end and on the other end is pivotally connected to the burner pipe 100 extending into the auxiliary shoe 29.

Pivots mounted on the inside of the tops of the frames 15 and 16 is a feed table 103. This feed table, when in the position shown in full lines in Figs. 1, 2, 3 and 4, is in cooperative relation to the ironing roll 28. Owing to the pivotal support of the feed table and the fact that its width is less than the space between the arms 77, said feed board may be moved to a covering position over the roll 18 and the shoe 23, as shown in dotted lines in Fig. 2. When in this position, the feed table protects the roll and shoe from dust.

Hinged to the edge of the table 46 is a delivery board 105 which is movably held in either of the positions shown in full and dotted lines by notched bars 106 pivotally secured to the bottom of the delivery board 105, and cooperating with pins 107 supported by the frames 15 and 16. The delivery board 105 may also be dropped to a vertical position if desired.

Slidably supported beneath the table 46, is an auxiliary table 109 which may be pulled out beyond the end of the machine beneath the auxiliary ironing roll 28 and the auxiliary shoe 29. This provides the operator with a table upon which to lay articles when the auxiliary ironing roll and shoe are in use.

Extending from the front of the upper part of the frames 15 and 16 are perforated lugs 112 and 113 adapted to receive a bracket 114 having projecting portions arranged to engage the holes in said lugs. Secured to this bracket is a wooden bar 115 which may be swung to any desired position and used to support articles which are to be or have been ironed.

What is claimed is:

1. In an ironing machine, the combination of an ironing roll, a shoe cooperating therewith, a frame in which said ironing roll and shoe are supported, and means for yieldingly and removably holding said shoe in cooperative engagement with said ironing roll comprising manually movable cams pivotally supported in said frame, springs, a rod extending through each spring and connected at one end to said spring and at the other end with the corresponding cam, a

connection between the other end of each of said springs and said shoe, said cams being so formed and said rods being so connected thereto that in one position said cams allow the springs to hold the shoe in yielding contact with the ironing roll and in other positions move and hold the shoe away from the ironing roll to different distances.

2. In an ironing machine, a frame, an ironing roll journaled in said frame, a shoe cooperating with said roll, a support for said shoe, a pin mounted on said frame and cooperating with a slot in said shoe, whereby the surface of said shoe may adapt itself to the contour of said ironing roll, and means for yieldingly and removably holding said shoe in cooperative engagement with said ironing roll comprising manually movable cam pivotally supported in said frame, springs, a rod extending through each spring and connected at one end to said spring and at the other end with the corresponding cam, and a connection between the other end of each of said springs and said shoe, said cams being so formed and said rods being so connected thereto that in one position said cams allow the springs to hold the shoe in yielding contact with the ironing roll, and in other positions move and hold the shoe away from the ironing roll to different distances.

3. In an ironing machine, a frame, an ironing roll journaled in said frame, a shoe cooperating with said roll, a support for said shoe, a pin mounted on said frame and cooperating with a slot in said shoe, whereby the surface of said shoe may adapt itself to the contour of said ironing roll, and means for yieldingly and removably holding said shoe in cooperative engagement with said ironing roll comprising springs, manually movable cams, a connection between one end of each of said springs and the corresponding cam, and a connection between the other end of each of said springs and said shoe, said cams being so formed that in one position they allow the springs to hold the shoe in yielding contact with the ironing roll and in other positions move and hold the shoe away from the ironing roll to different distances.

In witness whereof, I hereunto subscribe my name this 6th day of August A. D., 1920.

CHARLES E. REDDIG.
